Des. 229,415
Patented Nov. 27, 1973

229,415

PIPE COUPLING FITTING

Lawrence F. Luckenbill and Richard A. Stultz, Decatur,
Ill., assignors to Mueller Co., Decatur, Ill.

Filed Nov. 23, 1971, Ser. No. 201,626

Term of patent 14 years

Int. Cl. D23—01

U.S. Cl. D23—43

FIG. 1

FIG. 2

FIG. 3

FIG. 4

FIG. 1 is a side elevational view of a pipe coupling fitting embodying our new design;

FIG. 2 is an end elevational view taken from the right of FIG. 1;

FIG. 3 is an end elevational view taken from the left of FIG. 4; and

FIG. 4 is a top plan view thereof.

We claim:

The ornamental design for a pipe coupling fitting, as shown.
